CLAIM

I claim the ornamental design for the all terrain vehicle, as shown and described.

DESCRIPTION

FIG. 1 is a perspective view of the all terrain vehicle of the present design application;

FIG. 2 shows a left side view of the rear portion shown in FIG. 1;

FIG. 3 shows a right side view of the rear portion shown in FIG. 1; and

FIG. 4 shows a top view of the rear portion shown in FIG. 1; and,

FIG. 5 is an enlarged, left side view of the rear portion shown in FIG. 1 with unclaimed subject matter removed for clarity. The broken lines in the drawings show environment or structure and form no part of the claimed design.
